LIFT TRUCK

Bronislaus I. Ulinski, Chicago, Ill., assignor to
The Yale & Towne Manufacturing Company,
Stamford, Conn., a corporation of Connecticut

Application August 15, 1946, Serial No. 692,465

29 Claims. (Cl. 214—113)

1

This invention relates to an industrial truck of the type in which a load elevating carriage is adapted to lift and lower a load. More particularly, my invention relates to a truck of the particular class in which the carriage may not only be lifted and lowered, but may be tilted for effective manipulation of the load carried thereby.

In trucks of the particular class described, it is customary to mount the elevating carriage for lifting movement on a pair of secondary uprights. The secondary uprights are in turn mounted for lifting movement on primary uprights. For accomplishing this movement of the elevating carriage and the secondary uprights, it is customary to use a hydraulic ram, the ram operating through a chain mechanism and thereby imparting lifting movement simultaneously to the carriage and the secondary uprights.

As those skilled in the art will fully appreciate, it is very important that the load elevating carriage be capable of some lifting movement prior to the movement of the secondary uprights, so that the overall height of the truck shall not be increased when the carriage is lifted a limited amount. This arrangement is especially necessary where a truck is to be used for moving loads in and out of freight cars, since there it is essential that the overall height of the truck be maintained a minimum, while the load elevating carriage is raised to a considerable height to stack the load within the freight car or to remove it from a stack within the car. It is also necessary in trucks of the particular class that the elevating ram itself be not unduly exposed and that it shall not extend above the primary or secondary uprights during the lifting movement of the elevating carriage.

Inventors have attacked the particular problem for many years, but no very effective results have been obtained. One attempted solution of the problem is found in the Dunham Patent No. 2,178,370 dated October 31, 1939, where the elevating ram is adapted to raise the elevating carriage through means of a chain mechanism, while adapted to elevate the secondary uprights through direct physical contact. This direct physical contact is not made until after the ram moves a predetermined degree to lift the elevating carriage a short distance from the ground. While the Dunham structure is effective in maintaining the secondary uprights in their lowered position while simultaneously lifting the elevating carriage somewhat, the amount of lift of the carriage thus obtained is naturally very limited. It, therefore, becomes impossible to utilize the carriage effectively for stacking loads within a freight car, because to obtain a really considerable lift of the carriage, it is necessary to raise the secondary uprights somewhat.

2

I have conceived an effective solution of the problem presented, and have actually constructed a successfully operating and commercially desirable truck based on that conception. As a feature of my invention, I utilize two rams with one ram adapted to lift the load elevating carriage relatively to the secondary uprights while the second ram lifts the secondary uprights relatively to the primary uprights.

10 As a further feature of the invention, the second ram lifts both the secondary uprights and the load elevating carriage.

15 As a still further feature of my invention, one ram extends between the secondary uprights and the elevating carriage and is adapted to lift the elevating carriage, and while this may be done directly, I prefer to utilize a flexible movement multiplying mechanism such as a cable or chain that is actuated by the ram. The second ram to which I have alluded is supported for extension between the primary uprights and the secondary uprights and is adapted to lift the secondary uprights and therefore the elevating carriage also, and such movement may be accomplished directly or through the same sort of mechanism that is utilized in connection with the first ram for lifting the carriage.

20 It is a feature of this part of the invention that relatively small inexpensive rams may be utilized, as each ram is required to contribute relatively short movement to the mechanism actuated thereby. This is an exceedingly important characteristic of my invention, as those skilled in the art will appreciate.

25 As a further feature of my invention, the two rams are adapted to operate in sequence with the first ram lifting the load elevating carriage to its full extent before any movement whatsoever is imparted to the secondary uprights by the second ram. It is a particular important feature of my invention that this sequential operation is inherent in my structure so that both rams may be directly connected to a single source of fluid pressure. The operation is inherent because the fluid pressure will first actuate that ram having the lighter load with relation to its surface area, and will then actuate the ram having the greater load with relation to its surface area.

30 35 40 45 50 55 60 For purposes of economy, my rams are duplicates, and since one ram is required to lift merely the elevating carriage while the other ram is required to lift both the carriage and secondary uprights, it is obvious that the carriage will be the first load to be lifted. For insuring this sequential lift, those skilled in the art may develop other structures based on my broad concept of two sequentially actuated rams and it is naturally important that the claims granted me shall be of sufficient scope to cover such modifications of my invention. As a matter of fact, I have already conceived the utilization of a larger area

rain to raise the load elevating carriage, thereby reducing the unit area pressure required to lift the carriage relatively to the unit area pressure required by the second ram, and thus insuring the operation of the first ram where friction or other factors may place unforeseen difficulties on the carriage operation. Similarly, I have conceived the utilization of valving means, and even separate pressure sources and separate motors for those pressure sources, all designed to contribute the sequential lift I require, and all based on my broad concept of two rams.

As a further feature of my invention, the load elevating carriage and the secondary uprights are always maintained under the control of the hydraulic rams so that neither the carriage nor the secondary uprights may drop freely and cause damage. In the most successful structure of this type heretofore contributed, the secondary uprights may drop and cause considerable damage, and it has heretofore been possible only to limit this damage by limiting the amount of possible drop, and not to eliminate the difficulty. Those skilled in the art will appreciate greatly this particular phase of my invention and the considerable contributions made thereby to the art.

As still a further feature of the invention, I utilize a tilting ram for tilting the primary and secondary uprights together with the load elevating carriage relatively to the main frame of the truck. Insofar as the general arrangement of the tilting ram is concerned, there is no particular novelty therein to be claimed. However, the control of the tilting ram and the means whereby hydraulic pressure is directed thereto and therefrom, are of extreme importance and are herein to be described and claimed.

Thus, as a feature of my invention, the fluid pressure normally directed to the tilting ram will be directed to the lifting rams to augment the normal pressure applied to the lifting rams when the control for the tilting ram is in neutral position. As a particular feature of this part of the invention, the lifting rams and tilt ram are actuated from a single source of fluid pressure, in effect, with a part of the pressure going to the tilting ram and a part thereof going to the lifting rams, the arrangement being such that the fluid pressure will go entirely to the lifting rams if valve means are actuated for preventing the flow of fluid to either end of the tilting ram.

As a still further feature of my invention, I arrange for novel electrical controls for a motor utilized to develop a source of fluid pressure for the rams. Thus, it is possible to control the lift rams to lower the load without starting the motor, while at the same time, the actuation of the control means for the lift ram to lift the load, will start the motor, the starting of the motor being also accomplished upon movement of the control means for the tilt ram for tilting the load in either of opposed directions.

I have thus outlined rather broadly the more important features of my invention, in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate as I have already indicated, that the conception on which my disclosure is based, may readily be utilized as a basis for the designing of other structures for carrying out the several pur-

poses of my invention. It is important therefore that the claims to be granted me shall be of sufficient breadth to prevent the appropriation of my invention by those skilled in the art.

Referring now to the drawings, Fig. 1 is a side elevation of an industrial truck of the general class described, illustrating my invention applied thereto. Fig. 2 is a forward end elevation of the truck of Fig. 1. Fig. 3 is a view of the uprights 10 and the load elevating carriage with the carriage in its fully elevated position relatively to the secondary uprights. Fig. 4 is an end elevation of the parts in the position of Fig. 3. Fig. 5 is an elevation of the uprights and the elevating carriage showing both the carriage and secondary uprights in their fully lifted position. Fig. 6 is an end elevation of the parts of Fig. 5. Fig. 7 is a perspective view showing the chains utilized for lifting the carriage and/or secondary uprights with the ram actuated sprockets in engagement therewith. Fig. 8 is a diagrammatic view showing the lift and tilt rams, the fluid pressure source, and the valve mechanism and electrical mechanism for controlling the entire combination of elements.

Referring now more particularly to the drawings, the truck of my invention is of the general type well known in the art and having a load elevating carriage 10, a pair of secondary uprights 11, and a pair of primary uprights 12. The primary uprights, together with the secondary uprights and the carriage 10, are adapted for tilting in a manner indicated by me in earlier patents, or as hereinafter set forth. While the traction of my truck is obtained electrically, the lifting of the secondary uprights and load elevating carriage is obtained hydraulically.

Thus, the traction wheels 13 are driven in a conventional manner by an electric motor energized in the usual conventional manner, with the source of current being a battery contained in the battery compartment 14 of the truck illustrated. The operator of the truck will sit on the seat 15 and will steer the truck by means of the steering wheel 16. A pair of handles 17 and 18 are pivoted on an axis 19 relatively to a forward standard 20 of the truck, the handle 17 actuating a control rod 21 and the handle 18 actuating a control rod 22, both rods being best illustrated in Fig. 8.

The source of fluid pressure to which I have alluded is designated generally by the reference letter S in Fig. 1, and is probably best illustrated in Fig. 8. It comprises an electric motor 23 driving through gearing 24 a pair of pumps 25, 26. The two pumps 25, 26 are functionally considered one source of fluid pressure, it being more economical for my purposes to utilize two pumps rather than a single large pump. Both pumps obtain their fluid from a reservoir R, and the flow of fluid is effectively controlled by a tilt control valve mechanism T and a lift control valve mechanism L, mechanism T being actuated and controlled in turn by handle 17 and shaft 21, while mechanism L is controlled and actuated by handle 18 and shaft 22.

The load elevating carriage 10 is suitably secured to a vertically moving mounting member 27 that through opposed upper and lower rollers 28 and 29 is adapted to move vertically in the bearing channels 30 of the secondary uprights 11. The secondary uprights are in turn secured to a carrying member 31 that is equipped with upper and lower pairs of rollers 32 and 33 moving in the channels 34 of primary uprights 12.

In this way the secondary uprights may move relatively to the primary uprights. The primary uprights may be mounted in any suitable way, as those skilled in the art will fully appreciate, for tilting movement relatively to the truck. For the purposes of the present invention, I show at 35 stud shafts on which the uprights may tilt relatively to the truck main frame.

For accomplishing this tilting movement, I utilize a tilting ram designated generally by reference numeral 36 and comprising a ram piston 37 best illustrated in Fig. 8. This ram piston is pivoted at 39 to a lever 40 that is in turn pivoted at 41 on the standard 20 of the truck. At 42 there is pivoted to the lever 40 a link 43 that is pivoted at 44 to a bracket 45 forming an integral part of the primary uprights 12. It is now obvious that movement of the ram piston 37 will effect a tilting movement of the primary uprights 12 and therefore a pivotal movement of the secondary uprights and load elevating carriage 10.

For moving the load elevating carriage 10 and its mounting member 27 on rollers 28 and 29 relatively to the secondary uprights 11, I utilize a ram designated generally by reference numeral 46 pivotally supported at 47 on the secondary uprights. Instead of the pivotal support 47 the ram may simply be mounted in a universal cup-like bearing to be carried by the secondary uprights 11. The ram piston of the ram 46 is designated by reference numeral 48, and carries at its upper end a transverse bar 49 pivoted thereto at 50, as best seen in Fig. 7. At each end of the bar 49 there is mounted a sprocket 51, and the teeth of each sprocket are in engagement with a chain 52. Each of the chains 52 is secured at one end to the carriage 10 through means of a bracket 53, and is secured at its other end to a bracket 54 carried by the secondary uprights 11. It is, of course, obvious that upward movement of the ram piston 48 of ram 46 will effect a movement of the carriage 10 that will be double the movement of the ram piston 48. The movement that may be imparted thus to the carriage 10 is best illustrated in Figs. 3 and 4.

For lifting the secondary uprights and the carriage 10 as a unit relatively to the primary uprights 12, there is utilized a second ram 55 pivoted at 56a on the primary uprights 12, and having a ram piston 56. Ram piston 56 is connected at its upper end to a cross bar 57 that is a duplicate of the cross bar 49 actuated by the first ram piston 48. Through suitable sprockets 58 secured at each end of the bar 57 a second pair of chains 59 is actuated, these chains being secured at one end to the secondary uprights at 60, and at the other end to the primary uprights at 61. It is quite obvious that upward movement of the second ram piston 56 will contribute a double lift movement to the secondary uprights 11 in the same manner as a double lifting movement is contributed by the first ram piston 48 to the load elevating carriage 10.

In Figs. 5 and 6 the secondary uprights are shown at their highest lifted point, and the load elevating carriage 10 is shown lifted to its highest degree relatively to the secondary uprights. A study of Figs. 1, 3 and 4 illustrates the extremely high movement that may be imparted to the load elevating carriage prior to any movement of the secondary uprights. Thus, the dotted and dash line position of the forks 62 in Fig. 3 illustrates the height to which the lower

edge of the load elevating carriage 10 may be elevated without the upper end 63 of the carriage extending above the primary and secondary uprights 12, 11, and without any lifting of the secondary uprights 11. The other figures to which reference has been made illustrate very well the extremely high lift possible when both the load elevating carriage and the secondary uprights have been fully lifted.

10 As is probably best illustrated in Fig. 8, the first ram 46 and the second ram 55 both receive their fluid from the pipe 65, so that fluid pressure will inherently be applied first to that ram having the lightest load in proportion to its area. 15 Thus, from the pipe 65 fluid will flow to the fitting 66 and thence through pipe 67 to ram 55 or through pipe 68 to fitting 69 and then pipe 70 to ram 46. It will be understood that while I use the term pipe to designate the means through 20 which the fluid flows, it is actually desirable and even necessary to use flexible hose for conducting the fluid. Now, since the second ram 55 must lift everything that the first ram lifts, plus the first ram and the secondary uprights, it is obvious 25 that with the rams both the same size, the pressure required to actuate ram 55 will be greater than the pressure required to actuate ram 46. Therefore, piston 48 will be the first to move on the flow of fluid through pipe 65, and it will 30 not be until ram 46 has first elevated load elevating carriage 10 to the position of Figs. 3 and 4, that fluid will flow into ram 55 for actuating that ram and for lifting the secondary uprights together with the load carriage to the position illustrated in Figs. 5 and 6.

I believe that with this explanation, taken together with the general discussion of my invention already set forth, this phase of the contribution of my invention will be fully and clearly 40 understood. I do wish to emphasize at this point, that both the elevating carriage and the secondary uprights are always under the control of the two rams so that it is never possible to have a free floating pair of uprights as in prior art constructions.

45 Referring now further to Fig. 8, reference letter T, as already set forth, indicates the tilt control valve while reference letter L indicates generally the lift control valve. Referring first to the tilt control T, we find that it includes a chamber 70 in which slides a spool valve body 71 controlled by a portion 72 of the rod 21 through the scalloped or bored abutments 73 and 74 on the said rod. We find further in the tilt control T a spring loaded ball valve 75, with the pressure of spring 76 thereof controlled by an adjusting mechanism 77, the purpose of which will be explained presently. In the upper portion of the tilt control T we find a further chamber 78 within which floats a control piston 79 having a pair of opposed pins 80 for controlling a right hand ball valve 81 and a left ball valve 82.

Each of these said ball valves 81, 82 is maintained within a bore formed in the end portion 65 83 of a regulator valve body designated generally by reference numeral 84. There is one regulator valve for each side of the tilt ram 36, used for a purpose presently to be described. A further bore 85 is formed in the body of each of the regulator valves, and mounted within each bore 85 is a compression spring 86 guided at one end by a pin 87 and extending between the end of the bore 85 and a controlling sliding piston valve 88 whereby to maintain the said sliding piston valve 70 75 in its extreme right hand position illustrated in

Fig. 8. The construction of the sliding piston valve 88 is such that pressure applied thereagainst through its flanged surface 89 surrounding its speed control passage 89a, will tend to move the piston valve against the force of the spring 86 and into a position obstructing bores 90, all for a purpose presently to be disclosed.

The rod 21 for controlling the spool valve 71 of the tilt valve control T is formed with a dwell 91 cooperating with a control pin 92 for closing a switch at 93 upon movement of the rod 21 to the right or to the left from its position of Fig. 8.

I should now like to refer to the lift control valve L shown in Fig. 8. In the upper portion of this lift control valve L, there is shown a bore 94 within which is mounted a regulating valve 95 very similar in construction to the regulating valve shown in the tilt control T except that the end portion 63 containing the ball valve 81 is not utilized. Thus, regulating valve 95 contains a sliding control piston 96 pressed to the extreme right position by a spring 97 and adapted to move against the force of the spring when fluid pressure is exerted against the flange 98 of the said sliding piston surrounding its speed control passage 89a.

A chamber 99 is formed in the control valve L, and is closed by a plug 100. The plug 100 maintains in position a compression spring 101 that presses a ball 102 into closing relation to a bore 103 formed in a moving control piece 104. Mounted for sliding movement also in the chamber 99, and relatively to the control piece 104, is a valve body 105.

The control rod 22 is formed with a long dwell 106 so that movement to the right thereof for a considerable distance will not move the switch operating pin 107 that controls a switch 108. Movement of the rod 22 to the left in Fig. 8 will, however, move the pin 107 to close the switch 108. An index ball 109 co-acts with three index notches 110 in the rod 22 for indexing its three positions. Additional passages and means in the valve body L will be referred to later. It will be well now to disclose the operation of my invention under several conditions.

Let us first assume that the operator wishes to lift the load, but not to tilt the load. He will, therefore, leave the valve control rod 21 and the handle 17 in the neutral position illustrated in Fig. 8. He will move the handle 18 so as to move control rod 22 of control valve L to the left from the position of Fig. 8. This movement to the left will close a circuit at 108 and will excite the motor 23 which will immediately actuate pumps 25, 26. Simultaneously, the control surface 111 of rod 22 will move into position to close the right hand end of valve passage 112. Fluid will now flow from the reservoir through pump 26, pipe 113, and passage 114 to lift the ball valve 115. The flow will continue through passage 116, passages 117, 118, 119 of the regulator valve 95, through the bore 120 and speed control passage 98a of the piston 96, and into pipe 65. From pipe 65 the fluid will flow first into the ram 46 to lift the elevating carriage, and thereafter will flow into the ram 55 to lift the secondary uprights and the carriage, all as has been previously described. Safety valve 114a will of course prevent the application of additional pressure upon full lifting of the rams as those skilled in the art will appreciate.

At the same time, fluid will flow from the reservoir R into the pump 25 and through the pipe 121 into passage 122 of control valve T. Be-

cause spool 71 is positioned to prevent the flow of fluid into the chamber 78 of control valve T, the fluid can then flow only into passage 133 and through the bore 71a of spool 71 about the stem 72 of rod 21 and into chamber 70. Thence, it will flow through passage 78a and pipe 123 into pipe 113 and join the output of the first pump 26 in the actuation of the two lift rams 46, 55. Thus, the entire output of fluid pressure source S is used to actuate the two lift rams.

Let us say that the load has been fully lifted and that the operator wishes to lower the load. In order to stop the operation of the pumps 25, 26, the operator need only restore control rod 22 to its position of Fig. 8. This will hold the load in any elevated position to which it has been moved, as fluid cannot flow past ball valve 115. Thereafter, to lower the load he moves the rod 22 toward the right in Fig. 8 so that the pin 107 forming the end of the rod 22 unseats the ball 102. Once ball valve 102 is unseated, the pressures in the low pressure chamber 126 and in chamber 99 tend to become equalized. Therefore, the considerable pressure exerted by the fluid tending to flow from the rams 46, 55 will be effective to move the control piece 104 and then the valve body 105 to the right from their positions in Fig. 8 to establish a flow of fluid past the valve seat 127 into the low pressure chamber 126. This allows fluid to flow from the lift rams through pipe 65, the speed control passage 98a and bore 120 of the control piston 96, and passages 119, 118, 117 into bore 116. The fluid then flows through port 125 and past valve seat 127 into chamber 126 and through pipe 128 back to the reservoir R. In this way, the fluid from the lift rams 55, 46 moves to the reservoir and the load is lowered, always under full control.

For controlling the lowering speed of movement, I utilize the control piston 96 within the regulator valve 95. Thus, should undue speed be developed in the rams, the considerable pressures will tend to operate against the flange 98 moving piston 96 to the left in Fig. 8. This movement will be against the pressure of the spring 97 and will tend to close the passages 119. This will immediately slow down the ram piston movements. It may, therefore, be said that the regulator valve 95 effectively controls the speed of lowering movement of the elevating carriage and the secondary uprights. Incidentally, it will be well to emphasize here that the lifting speed is also controlled by regulator valve 95 through its passage 98a, as all fluid to the rams must pass through passage 98a. Any excessive pressures will naturally be relieved by safety ball valve 114a.

We have now seen that during the lifting movement both pumps operate together to contribute lifting action. We have also seen that during lowering movement of the lifting rams, no power is utilized, but control of the lowering speed is maintained. Let us now consider what happens when the load is tilted, and not lifted or lowered. In the event it is desired to tilt the load, but neither to lift nor lower, the control rod 22 is maintained in its position of Fig. 8. The control rod 21 is moved in one direction or the other depending upon the direction of the tilt desired. Let us say that it is desired to tilt in a direction in which the piston 37 of the ram 36 is moved upwardly in Fig. 8. For the particular purpose the rod 21 will then be moved to the right to align groove 130 of spool 71 with bore 129. This will

close the circuit at switch 93 and the motor 23 will be energized to actuate both pumps.

Fluid from pump 25 will move through pipe 113, bore 112, chamber 126 and pipe 128 back to the reservoir. The fluid from pump 25 will go through pipe 121, bore 122, bore 129, the left groove 130 of spool 71 and into chamber 78 at the left side of piston 79. The fluid will then move past the ball valve 82 and the regulator valve 84 into pipe 131 and thence into ram 36 and against piston 37. Movement of the piston 37 will, of course, tilt the load. Simultaneously, fluid will flow from the other side of the piston 37 through pipe 132 into regulator valve 84. The fluid will flow through the valve 84 in the same manner as it was explained it flows through the regulator valve 95 of the lift valve control L. The application of pressure at the left side of the piston 79 in chamber 78 has in the meantime forced the piston to the right from its neutral position of Fig. 8 so that its pin 80 has unseated ball valve 81. Therefore, fluid may flow through the regulator valve past the ball valve 81 into the right hand side of chamber 78 and thence through bore 133 and central bore 71a of spool 71. From bore 71a fluid flows through the scalloped or bored passages in abutment 74 to the left of said abutment and into chamber 70. From chamber 70 the fluid will flow through bore 70a into pipe 123 and thence will join the output of the pump 26.

It is well to consider at this point that the ball valve 75 must be so loaded by spring 76 under adjustment mechanism 77 that the fluid from pump 25 will move through the bore 129 to actuate the tilt ram rather than to by-pass the tilt ram by unseating the ball valve 75. It is well to consider also that the speed control passages 89a will determine the speed of tilt with all excess pressures relieved by flow of fluid past ball valve 75.

Let us now consider what happens when it is desired both to lift the load and tilt it. For the particular purpose the control rod 22 is then moved toward the left to excite the motor 23 so that the pump 26 pumps fluid as earlier described into the two rams 46, 55. Simultaneously the pump 25 will direct fluid towards one or the other of two ends of the ram 36 under the control of the spool 71. The fluid returning from the other side of the ram 36 will be at sufficiently high pressure so as to move through the bore 133 of the spool and through the pipe 123 to the pressure side of the pump 26. The nature of my system is such that the pressure at each side of the ram 36 is quite great, with the differential relatively small because of the relatively light load moved by the tilt ram as compared to the load moved by the lift rams. Because of this relationship between the pressures at the two sides of the piston 37, the pressure of the fluid flowing from behind the moving piston 37 will be sufficient to allow the entry of the fluid into the pressure side of the pump 26 for movement therewith to actuate the rams 46, 55.

I believe that with this description of the operation and control of the hydraulic mechanism, those skilled in the art will fully appreciate and understand the basis of my contribution to the art.

I claim:

1. In a truck of the class described, primary uprights, secondary uprights, means mounting

said secondary uprights for vertical movement relatively to said primary uprights, a load carriage, means mounting said load carriage for vertical movement relatively to said secondary uprights, a hydraulic ram interposed between said load carriage and secondary uprights, means whereby said hydraulic ram lifts said load carriage relatively to said secondary uprights and hold said carriage in an elevated position relatively to said secondary uprights, a second hydraulic ram interposed between said secondary uprights and primary uprights, and means whereby said secondary ram lifts said secondary uprights together with said load carriage relatively to said primary uprights while said first ram is conditioned to hold said load carriage elevated relatively to said secondary uprights.

2. In a truck of the class described, primary uprights, secondary uprights, means mounting said secondary uprights for vertical movement relatively to said primary uprights, a load carriage, means mounting said load carriage for vertical movement relatively to said secondary uprights, a ram for lifting said load carriage relatively to said secondary uprights extending between said secondary uprights and load carriage, and a second ram extending between said primary uprights and secondary uprights for lifting said secondary uprights relatively to said primary uprights.

3. In a truck of the class described, primary uprights, secondary uprights, means mounting said secondary uprights for vertical movement relatively to said primary uprights, a load carriage, means mounting said load carriage for vertical movement relatively to said secondary uprights, a ram for lifting said load carriage relatively to said secondary uprights supported on said secondary uprights, and a second ram for lifting said secondary uprights relatively to said primary uprights and therefore also said load carriage and first ram relatively to said primary uprights.

4. In a truck of the class described, primary uprights, secondary uprights, means mounting said secondary uprights for vertical movement on said primary uprights, a load carriage, means mounting said load carriage for vertical movement on said secondary uprights, a first ram supported on said secondary uprights, a flexible member secured at one end to said load carriage and at its other end to said secondary uprights, means whereby said first ram actuates said flexible member to lift said load carriage, a second ram supported on said primary uprights, and means whereby said second ram lifts said secondary uprights together with said first ram and load carriage.

5. In a truck of the class described, primary uprights, secondary uprights, means mounting said secondary uprights for vertical movement relatively to said primary uprights, a load carriage, means mounting said load carriage for vertical movement relatively to said secondary uprights, a first ram, a flexible member secured at one end to said load carriage and at its other end to said secondary uprights, means whereby said first ram actuates said flexible member to lift said load carriage relatively to said secondary uprights, a second ram, a flexible member secured at one end to said secondary uprights and at its other end to said primary uprights, and means whereby said second ram actuates said flexible member to lift said secondary up-

rights together with said first ram and load carriage relatively to said primary uprights.

6. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights, a second hydraulic ram for lifting said secondary uprights relatively to said primary uprights, a source of hydraulic pressure, and the said rams being of such size as compared to the loads imposed thereon that the first of said rams is actuated from said source of hydraulic pressure automatically in advance of the second ram.

7. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights, a second hydraulic ram for lifting said secondary uprights relatively to said primary uprights, a source of hydraulic pressure connected for the simultaneous flow of fluid to both rams, the said rams being of such size as compared to the loads imposed thereon that the fluid pressure required to actuate the first ram is less than that required to actuate the second ram whereby said first ram will lift said load carriage and thereafter the second ram will lift said secondary uprights.

8. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights supported on said secondary uprights, a second hydraulic ram supported on said primary uprights for lifting said secondary uprights together with said load carriage and first ram relatively to said primary uprights, a source of hydraulic pressure, and the said rams being of such size as compared to the loads imposed thereon that the first of said rams is actuated from said source of hydraulic pressure automatically in advance of the second ram.

9. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights, a second hydraulic ram for lifting said secondary uprights relatively to said primary uprights, and a source of hydraulic pressure connected to both said rams to actuate said rams in the order of the pressures required to actuate said rams.

10. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights supported on said secondary uprights, a second hydraulic ram supported on said primary uprights for lifting said

secondary uprights together with said load carriage and first ram relatively to said primary uprights, and a source of hydraulic pressure connected to both said rams to actuate said rams in the order of the pressures required to actuate said rams.

11. In a truck of the class described, primary uprights, secondary uprights, means mounting said secondary uprights for vertical movement on said primary uprights, a load carriage, means mounting said load carriage for vertical movement on said secondary uprights, a first hydraulic ram supported on said secondary uprights, a flexible member secured at one end to said load carriage and at its other end to said secondary uprights, means whereby said first ram actuates said flexible member to lift said load carriage, a second hydraulic ram supported on said primary uprights, means whereby said second ram lifts said secondary uprights together with said first ram and load carriage, and a source of hydraulic pressure connected to both said rams to actuate said rams in the order of the pressures required to actuate said rams.

12. In a truck of the class described, primary uprights, secondary uprights, means mounting said secondary uprights for vertical movement relatively to said primary uprights, a load carriage, means mounting said load carriage for vertical movement relatively to said secondary uprights, a second hydraulic ram for lifting said secondary uprights relatively to said primary uprights, a source of hydraulic pressure connected to both said rams to actuate said rams in the order of the pressures required to actuate said rams, the first of said rams having a lighter load with relation to its surface area than the second ram to a degree sufficient to effect operation by said fluid first of said relatively lighter loaded ram and then of said relatively heavier loaded ram.

13. In a truck of the class described, primary uprights, secondary uprights, means mounting said secondary uprights for vertical movement on said primary uprights, a load carriage, means mounting said load carriage for vertical movement on said secondary uprights, a hydraulic ram for lifting said load carriage relatively to said secondary uprights supported on said secondary uprights, a second hydraulic ram supported on said primary uprights for lifting said secondary uprights together with said load carriage and first ram relatively to said primary uprights, a source of hydraulic pressure connected to both said rams to actuate said rams in the order of the pressures required to actuate said rams, the first of said rams having a lighter load with relation to its surface area than the second ram to a degree sufficient to effect operation by said fluid first of said relatively lighter loaded ram and then of said relatively heavier loaded ram.

14. In a truck of the class described, primary uprights, secondary uprights, means mounting said secondary uprights for vertical movement relatively to said primary uprights, a load carriage, means mounting said load carriage for vertical movement relatively to said secondary uprights, a first hydraulic ram, a flexible member secured at one end to said load carriage and at its other end to said secondary uprights, means whereby said first ram actuates said flexible member to lift said load carriage relatively to said secondary uprights, a second hydraulic ram, means whereby said second ram lifts said second-

ary uprights together with said first ram and load carriage, a source of hydraulic pressure connected to both said rams to actuate said rams in the order of the pressures required to actuate said rams, the first of said rams having a lighter load with relation to its surface area than the second ram to a degree sufficient to effect operation by said fluid first of said relatively lighter loaded ram and then of said relatively heavier loaded ram.

15. In a truck of the class described, primary uprights, secondary uprights, means mounting said secondary uprights for vertical movement relatively to said primary uprights, a load carriage, means mounting said load carriage for vertical movement relatively to said secondary uprights, a hydraulic ram, means whereby said ram lifts said load carriage relatively to said secondary uprights and holds said carriage in elevated relation to said secondary uprights, a second hydraulic ram, means whereby said second ram lifts said secondary uprights relatively to said primary uprights while said first ram holds said carriage fully elevated relatively to said secondary uprights, and a source of hydraulic pressure on said truck connected simultaneously to both said rams.

16. In a truck of the class described, primary uprights, secondary uprights, means mounting said secondary uprights for vertical movement relatively to said primary uprights, a load carriage, means mounting said load carriage for vertical movement relatively to said secondary uprights, a hydraulic ram for lifting said load carriage relatively to said secondary uprights supported on said secondary uprights, a second hydraulic ram supported on said primary uprights for lifting said secondary uprights together with said load carriage and first ram relatively to said primary uprights, and a source of hydraulic pressure on said truck connected to said rams.

17. In a truck of the class described, a lift ram for lifting a load carrying member of said truck, a tilt ram for tilting said load carrying member, a source of fluid pressure, means of communication between said source of fluid pressure and both ends of said tilt ram, means of communication between said source of fluid pressure and said lift ram, a direction valve for directing fluid under pressure from said source of fluid pressure to one end or the other of said tilt ram, a fluid passage positioned between said direction valve and lift ram to permit the flow of fluid to said lift ram in by-pass relation to said tilt ram when said direction valve is positioned in neutral and preventing flow of fluid to either end of said tilt ram, and means in said direction valve whereby said fluid passage is in communication with one end of said tilt ram when said direction valve directs fluid to the other end of said tilt ram.

18. In a truck of the class described, a lift ram for lifting a load carrying member of said truck, a tilt ram for tilting said load carrying member, a source of fluid pressure, means of communication between said source of fluid pressure and both ends of said tilt ram, a direction valve for directing fluid under pressure from said source of fluid pressure to one end or the other of said tilt ram and against flow to either end, and means in said direction valve automatically opening a flow passage from the low pressure end of said tilt ram toward said lift ram when communication is made between the high pressure side of said

source of fluid pressure and the other end of said tilt ram.

19. In a truck of the class described, a lift ram for lifting a load carrying member of said truck, a tilt ram for tilting said load carrying member, a pair of pumps, means of communication between the first of said pumps and both ends of said tilt ram, means of communication between the second of said pumps and said lift ram, a direction valve for directing fluid under pressure from said first pump to one end or the other of said tilt ram, fluid passage means in by-pass relation to said direction valve to permit the flow of fluid in by-pass relation to said tilt ram when said direction valve is positioned in neutral and preventing flow of fluid to either end of said tilt ram, means whereby said fluid passage means are in communication with one end of said tilt ram when said direction valve directs fluid to the other end of said tilt ram, said fluid then flowing through said fluid passage means to said lift ram to augment the normal pressure flow to said lift ram, a control valve between said lift ram and said second pump communicating with said fluid passage means, and means forming part of said control valve for directing fluid to said lift ram when in one position, while directing fluid both from said first pump and from said fluid passage means back to the low pressure side of both said pumps when in a second position.

20. In a truck of the class described, primary uprights, secondary uprights, bearing means mounting said secondary uprights for vertical movement on said primary uprights, a load carriage, bearing means mounting said load carriage for vertical movement on said secondary uprights, a pair of ram pistons, a source of hydraulic fluid pressure, means whereby fluid from said source is directed toward both ram pistons simultaneously, means whereby one of said ram pistons lifts said load carriage on said secondary uprights, and means whereby the other of said ram pistons lifts said secondary uprights on said primary uprights, the first of said ram pistons having a lighter load with relation to its surface area than the second ram piston to a degree sufficient to effect operation by said fluid first of said relatively lighter loaded ram piston and then of said relatively heavier loaded ram piston.

21. In a truck of the class described, primary uprights, secondary uprights, means mounting said secondary uprights for vertical movement relatively to said primary uprights, a load carriage, means mounting said load carriage for vertical movement relatively to said secondary uprights, a pair of ram pistons, a source of hydraulic fluid pressure, means whereby fluid from said source is directed toward both ram pistons simultaneously, a chain through which one of said ram pistons lifts said load carriage relatively to said secondary uprights, a second chain through which the other of said ram pistons lifts said secondary uprights and carriage together relatively to said primary uprights, the first of said ram pistons having a lighter load with relation to its surface area than the second ram piston to a degree sufficient to effect operation by said fluid first of said relatively lighter loaded ram piston and then of said relatively heavier loaded ram piston.

22. In a truck of the class described, primary uprights, secondary uprights, bearing means mounting said secondary uprights for vertical movement on said primary uprights, a load carriage, bearing means mounting said load car-

riage for vertical movement on said secondary uprights, a pair of ram pistons, means for directing fluid under pressure against said ram pistons, means whereby one of said ram pistons lifts said load carriage on said secondary uprights, and means whereby the other of said ram pistons lifts said secondary uprights on said primary uprights.

23. In a truck of the class described, primary uprights, secondary uprights, means mounting said secondary uprights for vertical movement relatively to said primary uprights, a load carriage, means mounting said load carriage for vertical movement relatively to said secondary uprights, a pair of ram pistons, means for directing fluid under pressure against said ram pistons, means whereby one of said ram pistons lifts said load carriage relatively to said secondary uprights, and means whereby the other of said ram pistons lifts said secondary uprights relatively to said primary uprights.

24. In a truck of the class described, primary uprights, secondary uprights, means mounting said secondary uprights for vertical movement on said primary uprights, a load carriage, means mounting said load carriage for vertical movement on said secondary uprights, a pair of ram pistons, a source of hydraulic fluid pressure, means whereby fluid from said source is directed toward both ram pistons simultaneously, a chain secured at one end to said load carriage and at its other end to said secondary uprights, means whereby one of said ram pistons acts on said chain to lift said load carriage on said secondary uprights, and means whereby the other of said ram pistons lifts said secondary uprights on said primary uprights, the first of said ram pistons having a lighter load with relation to its surface area than the second ram piston to a degree sufficient to effect operation by said fluid first of said relatively lighter loaded ram piston and then of said relatively heavier loaded ram piston.

25. An industrial truck comprising a body, a tandem mast structure pivotally mounted on the forward end thereof, guideways in the masts, traveling members in the guideways, a hydraulic lift on each mast for actuating the traveling members, the outer mast being supported by the traveling member in the inner mast, and a load-supporting fork supported by the traveling member in the outer mast.

26. In an industrial truck, a chassis, a first hydraulic lift comprising a mast supported on said chassis, supporting means associated with said mast, and a hydraulic motor for elevating said supporting means relative to said mast, a second hydraulic lift comprising a mast supported by said supporting means, a load-supporting platform, and a second hydraulic motor for elevating said platform relative to said second mast.

27. In a truck of the class described, primary uprights, secondary uprights, means mounting said secondary uprights for vertical movement relatively to said primary uprights, a load carriage, means mounting said load carriage for vertical movement relatively to said secondary uprights, a hydraulic ram interposed between said load carriage and secondary uprights, means whereby said hydraulic ram lifts said load carriage relatively to said secondary uprights and holds said carriage in all elevated positions relatively to said secondary uprights, a second hydraulic ram interposed between said secondary uprights and primary uprights, means whereby said secondary ram lifts said secondary uprights

together with said load carriage relatively to said primary uprights, and means for directing fluid simultaneously toward both said rams whereby to actuate said rams sequentially in the order of the pressures required to actuate said rams.

28. In a truck of the class described, a lift ram for lifting a load carrying member of said truck, a tilt ram for tilting said load carrying member, a source of fluid pressure, means of communication between said source of fluid pressure and both ends of said tilt ram, means whereby said lift ram is in communication with said source of fluid pressure in by-pass relation to said tilt ram whereby all the fluid pressure is utilized to actuate said lift ram, a direction valve for directing fluid under pressure from said source of fluid pressure to one end or the other of said tilt ram and also against flow to either end, and means in said direction valve automatically opening a flow passage from the low pressure end of said tilt ram toward said lift ram when communication is made between the high pressure side of said source of fluid pressure and the other end of said tilt ram.
29. In a truck of the class described, a tilt ram for tilting a load carrying member of said truck, a source of fluid pressure, means of communication between said source of fluid pressure and both ends of said tilt ram, a direction valve having direction passages for directing fluid under pressure from said source of fluid pressure to one end or the other of said tilt ram and against flow to either end, means forming a part of said direction valve positioned in by-pass relation to said direction passages to permit the flow of fluid in by-pass relation to said tilt ram when said direction valve is positioned in neutral and preventing flow of fluid to either end of said tilt ram, and said means automatically opening a passage from the low pressure end of said tilt ram to said means in by-pass relation to said direction passages when communication is made between the high pressure side of said source of fluid pressure and the other end of said tilt ram through one of said direction passages.

45 BRONISLAUS I. ULINSKI.
